ware

Application January 28, 1932, Serial No. 589,426
In Great Britain March 19, 1931

3 Claims. (Cl. 139—125)

This invention relates to looms and is particularly concerned with shuttleless looms of the type wherein a dummy shuttle is employed to carry a pre-formed loop through the shed of the warp threads. It is an object of this invention to provide an improved form of dummy shuttle for use in looms of this type.

The dummy shuttle employed for this purpose normally comprises a solid body having usually the general shape of an ordinary shuttle, and carrying two horns which point in opposite directions lengthwise of the shuttle, and are adapted to catch the weft loop at the side of the loom and enable the shuttle to carry it through the shed. With such shuttles, there is a tendency, particularly when artificial and other springy yarns are being used, for the weft to jump out of engagement with the horns, with the result that it is not laid properly in the shed. It is a particular object of the invention to devise a shuttle in which this disadvantage is avoided.

According to the invention, in a dummy shuttle for use in shuttleless looms the space between a weft engaging horn and the body of the shuttle is formed with a constriction which readily permits the passage of a weft loop during its engagement by the horn, but prevents the loop from springing out after its engagement.

Thus, a spring or tooth may be formed either on the horn or the shuttle body or on both so as partially to close the passage between the horn and the shuttle against the return of the loop, while allowing the loop to pass it smoothly and without hindrance as the horn enters the loop. Such a projection is arranged to present an angle to the weft, in which the weft is caught if it attempts to pass out of engagement with the horn. Thus, there may be provided on the body of the shuttle or on the horn a projection which causes the passage offered to the weft to converge towards the base of the horn, and which, beyond the narrowest point of the passage, falls away sharply. The projection may constrict the passage for the weft loop against its return by arranging that the projection enters a groove while leaving a space for the weft to pass during its engagement by the horn. This groove is formed in the shuttle body when the projection is formed on the horn, and on the horn when the projection is on the shuttle body.

The invention will now be described in greater detail with reference to the accompanying drawing, but it is to be understood that this description is given by way of illustration only and is in no way limitative.

Figure 1 is a side elevation in part section and Figure 2 a plan of a dummy shuttle according to the invention.

Figures 3, 4, 5 and 6 are sections across the lines 3—3, 4—4, 5—5, and 6—6 respectively on Figure 2.

Figures 7 and 8 are a side elevation and plan respectively of a portion of a further form of dummy shuttle according to the invention.

Figure 9 is a side elevation in part section of a portion of a further form of dummy shuttle according to the invention.

Referring to Figures 1 to 6, the dummy shuttle illustrated comprises a wooden body 11 having steel tips 12 and provided with a broad groove 13 along the upper side of the body 11. Two horns 14 are attached at their bases 15 by means of screws 16 to the top of the shuttle. The horns 14 curve round from their bases 15 to the side 17 of the shuttle away from the reed as the shuttle 20 passes through the shed, the horns 14 being bent round to lie flush with the side 17 and then passing along the length of the shuttle in the groove 13. Oblique slots 18 are thus formed between the shuttle and the horn on the side of the 25 shuttle away from the reed, the slots 18 sloping downwardly towards the mid-point of the shuttle and communicating at their lower ends through a space 19 with the under side of the shuttle and at their upper ends with the groove 13 on the top 30 of the shuttle at points near the shanks of the horns 14. The weft loop is presented to the dummy shuttle and passes under the tip of the horn 14 by means of which one limb of the loop which is held at the selvedge is conducted down 35 the groove 18 to the bottom of the shuttle, the free end of weft coming out through the space 19 between the curve of the horn and the body of the shuttle and running back along the groove 24 in the middle portion of the shuttle body. The 40 under side of the shuttle is channelled as indicated at 20 to allow the free passage of the weft beneath the shuttle and to permit it to be pulled taut from the selvedge, so that the proper tension is applied to the weft and a good selvedge is 45 formed. This feature is especially advantageous in the weaving of smooth and slippery yarns, such as artificial silk yarns, to which, on account of their smoothness, it is difficult to impart the correct tension.

In order to prevent the weft thread from coming out of its engagement under the horn 14, a tooth 21 is provided beneath the tip of each shuttle horn, which tooth restricts the passage between the tip of the horn 14 and the bottom of the groove 55

13, and prevents the weft, once engaged, from returning. If desired, the tooth 21 may be inserted on the shuttle body beneath the tip of the horn, instead of being disposed on the under-
5 side of the horn itself.

For the purpose of preventing the free end of the weft loop from riding up the edge of the groove 13 in the top of the shuttle and falling between the shuttle and the reed, the side 25 of 10 the groove nearest the reed may be undercut so as to present an overhanging edge 26. If any 15 springiness of the weft thread causes it to be pressed against the side 25 of the groove 13, it cannot ride up the side of the groove and over the edge of the shuttle on account of the overhanging edge 26. Thus the danger of disturbing the path of the shuttle by the engagement of the free end of the weft between the shuttle and the reed and the possibility of damaging the weft or 20 warp threads thereby is eliminated. The overhanging edge above referred to is particularly clearly seen in Figures 3 to 6.

Crevices in the shuttle body are avoided and all projections are carefully rounded off so that 25 if the shuttle should turn in the shed, there is no danger of its catching the warps. For the same reason, the shanks of the horns 14 are caused to lie flush with the side 17 of the shuttle, while the tips of the horns lie wholly within the groove 13.
30 In Figures 7 and 8 a tooth 23 is provided on the base 15 of the horn and projects into a hole 29 on the shank of the horn opposite the base, so that the passage through which the weft is conducted is completely closed. The free end of the weft 35 thread passes up from the bottom of the shuttle through the space 19, and it will be seen that in passing the tooth 28, the thread is kinked or distorted into the hole 29, the space 19 offering no way for the thread to spring out.

40 In Figure 9 a tooth 21 is provided under the tip of the horn 14 as in Figures 1 to 6, but in this case a recess 30 is provided into which the tooth 21 projects so that here also the shape of passage

between the tooth 21 and the recess 30 is such as to necessitate the kinking of the thread as the thread passes in, and will not permit it to pass out again.

What we claim and desire to secure by Letters Patent is:—

1. A dummy shuttle for use in shuttleless looms comprising in combination a body member and a horn member attached thereto and adapted to engage a pre-formed loop of weft, the passage between said members being narrowed over part of its length to form a constriction which widens rapidly towards the point of attachment of the horn member to the body member and less rapidly in the opposite direction, said constriction readily 15 permitting the passage of the weft loop during its engagement by the horn, but preventing such loop from springing out after engagement.

2. A dummy shuttle for use in shuttleless looms comprising in combination a body member and a horn member attached thereto and adapted to engage a pre-formed loop of weft, the passage between said members being tortuous and narrowed over part of its length so as to form a constriction which readily permits the free passage 25 of the weft loop during its engagement by the horn, but prevents such loop from springing out after engagement.

3. A dummy shuttle for use in shuttleless looms comprising in combination a body member and a horn member attached thereto and adapted to engage a pre-formed loop of weft, a projection being provided on one of said members which enters a recess in the other member, the passage so formed between said members being tortuous and narrowed over part of its length so as to form a constriction which readily permits the free passage of the weft loop during its engagement by the horn, but prevents such loop from springing out after engagement.
